(57) **CLAIM**

The ornamental design for a luggage cart, as shown and described.

DESCRIPTION

FIG. 1 is a top front left perspective view of the luggage cart of the present invention;
FIG. 2 is a top front right perspective view thereof;
FIG. 3 is a top view thereof;
FIG. 4 is a left side view thereof;
FIG. 5 is a right side view thereof;
FIG. 6 is a front view thereof;
FIG. 7 is a bottom front left perspective view thereof;
FIG. 8 is a bottom view thereof; and,
FIG. 9 is a bottom front right perspective view thereof.
The portions of the luggage cart shown in broken lines in the figures form no part of the claimed design.
